D. NELSON.

PLOW.

No. 44,442.

Patented Sept. 27, 1864.

UNITED STATES PATENT OFFICE.

DAVID NELSON, OF PORT WASHINGTON, OHIO.

PLOW.

Specification forming part of Letters Patent No. 41,442, dated September 27, 1864.

To all whom it may concern:

Be it known that I, DAVID NELSON, of Port Washington, in the county of Tuscarawas and State of Ohio, have invented a new and useful Improvement on the Plow; and I do hereby declare that the following is a full, clear, and exact description of the same.

My invention consists in an improvement on the plowshare, whereby a steel point may be applied upon the principle of the shank and socket to any of the plows in common use.

The share of cast-iron is made with margins and bearings to fit upon any plow to which it may be desired to attach it. It is some two or more inches shorter, also thicker and wider at its point or end. In the front end of the share there is a recess or socket of dimensions sufficient to receive the shank, on which is fixed the cutting point or bit. The shank is, say, two and one-half inches in length, three-eighths of one inch in thickness, and one and one-quarter inch wide, fitting accurately in the socket, where it is fastened with a pin or bolt. The head of this shank, which may be of steel or iron, constitutes the plow-point, and is made to correspond with the share to which it is intended to apply. About the middle of the socket A, I cast or drill a hole, *a*, through the upper and lower walls forming the socket.

The point B should be made of steel, or it may be made of wrought-iron, and the blade *b* faced with steel. The shank B' is accurately fitted to the socket, and a hole, *b'*, punched or drilled so as to nearly correspond with the hole *a* in the socket; but this hole should be a trifle nearer to the shoulder *c* of the point than the hole *a* is from the front end of the socket, so that when the pin or key *c'*, by which the two parts are fastened together, is driven in the shoulder *c* will thereby be drawn firmly against the end of the socket. The point can be removed for sharpening simply by driving out the pin *c'*. If from any cause the point B should incline to work loose in consequence of the wearing of either of the holes or key, a thin washer of metal may be interposed between the shoulder and the socket, and by driving the key will be made fast.

What I claim as my improvement, and desire to secure by Letters Patent, is—

A plowshare cast with a socket for the purpose of receiving and securing a steel point, in the manner and for the purpose herein set forth.

DAVID NELSON.
